Primary Examiner — Manpreet S Matharu*Assistant Examiner* — Suzanne E Tisdell(74) *Attorney, Agent, or Firm* — McInnes & McLane, LLP(57) **CLAIM**

The ornamental design for a vehicle hood, as shown and described.

DESCRIPTION

FIG. 1 is a top front perspective view of a vehicle hood showing our new design;

FIG. 2 is a top rear perspective view of the vehicle hood of FIG. 1;

FIG. 3 is a front view of the vehicle hood of FIG. 1;

FIG. 4 is a rear view of the vehicle hood of FIG. 1;

FIG. 5 is a left side view of the vehicle hood of FIG. 1;

FIG. 6 is a right side view of the vehicle hood of FIG. 1; and,

FIG. 7 is a top view of the vehicle hood of FIG. 1.

The dot-dash pattern broken lines show a claim boundary. Neither the broken lines themselves nor the area outside of the broken lines form any part of the claimed design.

1 Claim, 6 Drawing Sheets
